UNITED STATES PATENT OFFICE.

FRANK WILLHELM, OF DAYTON, OHIO, ASSIGNOR OF ONE-HALF TO LEVI SPIELMAN, OF SAME PLACE.

SEWING-MACHINE.

SPECIFICATION forming part of Letters Patent No. 244,102, dated July 12, 1881.

Application filed January 8, 1881. (No model.)

To all whom it may concern:

Be it known that I, FRANK WILLHELM, of Dayton, in the county of Montgomery and State of Ohio, have invented a new and useful Improvement in Sewing-Machines, of which the following is a specification.

My invention relates to a device by which the presser-foot is given a reciprocating movement, the motion being transmitted from a pin attached to the crank-plate engaging an angular lever with adjustment attachment secured to the arm-head, as will more clearly hereinafter appear. I attain the object by the mechanism illustrated in the accompanying drawings, in which—

Figure I is a front elevation of the arm-head. Fig. II is a side view of the operating mechanism. Fig. III is a rear view of the head-plate.

A represents the arm-head of the White sewing-machine, and B the head-plate.

The device is adapted to many sewing-machines in which a cam is attached to the needle-bar to give the requisite movement.

C is the shaft, which has bearings in the arm of the machine; J, the crank-disk, which carries the roller K, which operates the cam of the needle-bar.

The parts thus far described are common to sewing-machines of this class.

The pin O (see Fig. II and dotted lines at Fig. I) projects to the rear from the crank-disk. Its travel is indicated by the circular dotted line at Fig. I, showing the engagement with the adjusting-arm H, exhibited in front and side views in Figs. I and II.

The angular lever I and the adjusting-arm H are pivoted on a common screw attached to the head. The adjusting-screw enters the vertical portion of the lever, and its end rests

against the adjusting-arm. As this arm is carried inward by the screw the upward movement of the presser-foot is increased, and the reverse movement decreases said movement.

D is the needle-bar, and E the presser-bar. 45 To the latter is attached the ordinary guide G, which moves within a slot in the head-plate, and at the top of which is a rear projection, O², which is engaged by the lever I, and thus a reciprocating movement is given to the presser-foot. The pin O is so attached to the crank-disk as to raise the presser-foot slightly from the cloth after the loop is taken, but before the needle is raised out of the cloth; and the device thus operating is very useful in sewing 50 on braid, it being done smoothly, with a uniform stitch in sewing on, at an angle or short curve.

The operation is sufficiently apparent from the description already given. The pin engaging the lever at each rotation communicates a reciprocating movement to the presser-foot.

I am aware that a cam at the end of the shaft has been used in connection with an angular lever to produce a reciprocating motion to a 65 presser-foot of a sewing-machine, and I therefore only claim the device as set forth in my specification.

Having thus fully described my invention, what I claim, and desire to secure by Letters 70 Patent, is—

The pin O, the crank-disk J, the arm H, with the adjusting-screw F, and the angular lever I, in combination with the presser-bar E of a sewing-machine, substantially as shown and 75 set forth.

FRANK WILLHELM.
